[54] **USE OF CARBOXYMETHYL
HYDROXYETHYL CELLULOSE IN
FRACTURING FLUIDS**

[57] **ABSTRACT**

Carboxymethyl cellulose is not normally considered a good candidate as a thickener for fracturing fluids for

subterranean formations due to the poor salt sensitivity of its solutions. It has been found that if carboxymethyl cellulose is modified with hydroxyethyl functionality, the salt sensitivity of its aqueous solutions is improved to a point where it can be used in this application. Specifically, carboxymethyl hydroxyethyl cellulose having carboxymethyl D.S. of 0.7 to 1 and hydroxyethyl M.S. of 0.3 to 2 can be so employed.
